UNITED STATES PATENT OFFICE.

ARTHUR L. WALL, OF BOONVILLE, NORTH CAROLINA.

ACETYLENE-GAS GENERATOR.

1,268,650.

Specification of Letters Patent. Patented June 4, 1918.

Application filed October 11, 1916. Serial No. 125,037.

To all whom it may concern:

Be it known that I, ARTHUR L. WALL, a citizen of the United States, residing at Boonville, in the county of Yadkin and 5 State of North Carolina, have invented new and useful Improvements in Acetylene-Gas Generators, of which the following is a specification.

This invention comprehends the provision 10 of an apparatus for generating and storing acetylene gas, wherein use is made of vertically movable bells with one of which the carbide container is associated and adapted to be submerged within the water with a 15 consequent generation of gas.

The invention provides an apparatus of this character by means of which gas can be economically produced in the generator and stored both therein and in the storage 20 tank, from which latter the gas is initially discharged.

In carrying out the invention I construct the carbide container in a manner to prevent the generation of too much gas at one time, 25 together with means for conveying the gas from the main generating compartment to the interior of the bell with which the container is associated, with a view of equalizing the pressure therein which controls the 30 movements of the bell.

For the purpose of carrying these and other coördinate objects into effect, the preferred embodiment of the invention is illustrated and described, and embraced in the 35 scope of the appended claims.

In the drawings forming part of this specification like numerals of reference indicate similar parts in the several views and wherein:—

40 Figure 1 is a side elevation of the apparatus with certain parts broken away to show the interior construction.

Fig. 2 is a longitudinal sectional view 45 through the apparatus.

Fig. 3 is a horizontal sectional view there- 50 through.

Fig. 4 is an enlarged detail view of the carbide container.

The apparatus essentially consists of a 55 plurality of closely associated tanks, both of which are adapted to be filled with water to a predetermined level, one of the tanks constituting a generator indicated at 10 and the other a storage tank indicated at 11.

Rising centrally within each tank is a discharge pipe 12, the latter being branched off

laterally as at 13 adjacent the bottom of their respective tanks and extended through the corresponding side walls thereof and connected together by means of a valve controlled pipe 14 through the instrumentality of which communication is established between the pipes 12 and the respective tanks 10 and 11. A valve 15 is provided to control this communication, while rising from the 65 pipe 14 is a supply pipe 16 common to both of the discharge pipes 12 of the respective tanks.

Arranged within each tank for vertical adjustment is a bell 17, which latter has secured on the interior thereof spaced spiders 18 which are connected by means of a centrally disposed hollow member 19 which receives the discharge pipe 12 of its respective tank, whereby the pipes 12 constitute guides 75 for the bells as the latter are adjusted. Secured to two opposed walls of each of the respective tanks are cleats 20, while secured to the adjacent walls of the bells 17 adjacent the bottoms thereof are similar elements 70 21 adapted to abut against the cleats 20 as the bells are moved upwardly, in a manner to be hereinafter described, to limit the adjustment of the bells in this direction.

Forming a part of the bell 17 associated 85 with the generating tank 11 is a receptacle 22 disposed centrally thereof, and projecting an appreciable distance below the top wall of said tank. The receptacle is open at both ends, and thereby communicates with 90 the interior of the bell, and is adapted to receive the carbide container 23 which latter is of corresponding cross sectional configuration as the receptacle 22 and has its bottom and side walls perforated as shown. The 95 carbide container is provided with a swinging yoke or handle 24 to facilitate the insertion of the container within or its removal from the receptacle 22 as the occasion may require, the container when positioned within the receptacle resting upon the uppermost spider 18 of the bell 17. Secured to two opposed walls of the container interiorly thereof are lugs 25 upon which rests a partition 26 dividing the container into two 100 compartments so as to prevent too much gas being generated at one time, or in other words with one operation of the bell when it is lowered. A hollow tubular member 27 is passed centrally through the carbide container, extending through the partition 26, and is adapted to receive the discharge pipe 110

12 of the generating tank so that as the gas is generated a large portion of the same will be immediately conveyed through the pipe 12 of the tank 10 into the pipe 12 of the tank 11 through the connecting pipe 14, and subsequently stored in the bell 17 of the tank 11.

The receptacle 22 is preferably formed with spaced walls 28 for the reception of the sides 29 of a cover or closure 30 for the receptacle. The closure when in position is disposed slightly below the upper edge of the outer wall of the receptacle, and a rod 31 passed transversely across the closure, and through the alined openings in the outer 15 wall of the receptacle for the purpose of holding the cover in place. The space between the walls 28 of the receptacle is partially filled with water to provide a seal against the escapement of gas from the receptacle 22.

It is of course manifest that the bell 17 of the tank 10 gravitates to lowered position until the carbid container 23 is submerged in the water contained within the tank, whereupon the generation of gas takes place. As the gas is generated it is received by the bell 17, which latter under a predetermined pressure is elevated to remove the carbid container out of the water. As the carbid 25 within the container is still saturated, a surplus amount of gas is generated, and this gas is conveyed through the pipe 12 into the storage tank 11 in the manner above stated.

With a view of equalizing the pressure 35 within the bell 17 and the receptacle 22 as the gas is generated, I preferably employ a U-shaped pipe 32 secured to the receptacle 22 in any suitable manner, and having its limb 33 interposed between the receptacle 40 and the carbid container 23, while its other limb 34 is positioned within the bell 17 whereby the gas is immediately conveyed from the receptacle 22 into the bell 17 so that the latter will be elevated at the proper 45 time and prevent the carbid container from remaining in the water an undue length of time. Leading from that portion of the pipe 12 of the tank 10 that projects exteriorly thereof is a valve controlled outlet 35 to 50 permit the escape of air when the generator is charged.

The bell 17 in the tank 11 is weighted or heavier than the bell of the tank 10, so that when the latter mentioned bell has been 55 elevated to the limit of its adjustment the gas pressure within the tank 10 and tank 11 elevates the bell 17 in the latter mentioned tank to the limit of its adjustment. The bell in the tank 11 being weighted is the first 60 to gravitate as the gas is consumed from the supply pipe 16, with a consequent initial consumption of the gas in the storage tank 11. When the gas enters the supply pipe 16 it is in a wet condition, the water 65 being separated from the gas as the latter

passes through the filtering medium 36 arranged within the supply pipe as shown. The water then gravitates into a substantially U-shaped drain pipe 37 coupled to the lower end of the supply pipe 16, and by 70 reason of the formation of the drain pipe a certain amount of water is maintained therein to provide a seat against the escapement of gas therethrough. It might here be stated that the component parts of the 75 apparatus may be constructed from any suitable material, and of any desired dimensions, while each of the tanks 10 and 11 are provided with a water drain cock 38.

While it is believed that from the foregoing description the nature and advantages of the invention will be readily apparent, I desire to have it understood that I do not limit myself to this precise construction and arrangement of parts, and that such changes 85 may be resorted to when desired as fall within the scope of what is claimed.

What is claimed is:—

1. In a gas generator the combination with a tank having a supply pipe arranged vertically therein, of a vertically movable gas receiving bell arranged within said tank, spaced superimposed spiders arranged in said bell, a hollow tubular member connecting said spiders and projecting an appreciable distance above the uppermost spider, said tubular member slidably mounted upon said supply pipe, whereby the latter constitutes a guide for the bell, and a carbid container partly disposed within the bell and supported upon the uppermost spider. 90

2. In a gas generator, the combination with a tank, of a gas receiving bell movably arranged within the tank, said bell being closed at the top, spaced superimposed spiders arranged in said bell, a double-walled receptacle supported upon the uppermost spider and projecting an appreciable distance through an opening in the top of said bell, a perforated carbid container arranged within said receptacle and also resting upon the uppermost spider, means for guiding said bell in its movement, a cover common to both the receptacle and carbid container, and said cover including a cylindrical wall adapted to be positioned within the space between the walls of said receptacle as for the purpose described. 105

3. A gas generator comprising a tank, a vertically movable gas receiving bell arranged therein, spaced superimposed spiders fitted within said bell, said bell being closed at the top, a double-walled receptacle projecting below and above said top of the bell and resting upon the uppermost spider, a 110 perforated carbid container disposed within said receptacle and spaced therefrom, said carbid container also resting upon the uppermost spider, a cover common to both the receptacle and said carbid container, includ- 115

120

130

ing a cylindrical wall fitted within the space between the walls of said receptacle, a substantially U-shaped pipe having one branch interposed between said receptacle and the 5 carbid container, and its other branch positioned within the bell to convey the gas from the receptacle to the latter.

4. In a gas generator in combination with a tank, of a vertically movable gas receiving 10 bell arranged therein, spaced superimposed spiders fitted within said bell, said bell being closed at its top, a double-walled receptacle resting upon the uppermost spider and projecting an appreciable distance above the 15 bell through an opening in said top, a carbid

container arranged within the receptacle and also resting upon the uppermost spider, a closure common to both the receptacle and the carbid container, said closure embodying a cylindrical wall adapted to be fitted in 20 the space between the walls of said receptacle, said cover being disposed below the upper edge of said receptacle, and a transversely disposed rod secured to said receptacle and disposed above the cover for maintaining the latter operatively associated with the receptacle and said carbid container as described.

In testimony whereof I affix my signature.
ARTHUR L. WALL.
